CLAIM

The ornamental design for a crystal door lock, as shown and described.

DESCRIPTION

FIG. 1 is a perspective view of a crystal door lock showing my new design;

FIG. 2 is another perspective view of the crystal door lock thereof;

FIG. 3 is a front elevation view thereof;

FIG. 4 is a rear elevation view thereof;

FIG. 5 is a left view thereof;

FIG. 6 is a right view thereof;

FIG. 7 is a top plan view thereof; and,

FIG. 8 is a bottom plan view thereof.

The broken lines illustrate portions of the crystal door lock that form no part of the claimed design.
